UNITED STATES PATENT OFFICE

117,688

DESIGN FOR AN EVAPORATIVE COOLER CABINET

Willard E. Brown, Los Angeles, Calif.

Application May 29, 1939, Serial No. 85,246

Term of patent 7 years

To all whom it may concern:

Be it known that I, Willard E. Brown, a citizen of the United States, residing at Los Angeles, in the county of Los Angeles and State of California, have invented a new, original, and ornamental Design for an Evaporative Cooler Cabinet, of which the following is a specification, reference being had to the accompanying drawing, forming a part thereof.

Figure 1 is a front elevational view of the article, showing my design;

Figure 2 is a side elevational view;

Figure 3 is a rear elevational view; and

Figure 4 is a top plan view.

I claim:

The ornamental design for an evaporative cooler cabinet, as shown.

WILLARD E. BROWN.
